ABSTRACT OF THE DISCLOSURE

A collapsible plastic bottle-carrying container composed of four side walls so arranged as to define a cavity of rectangular horizontal cross-section, at least one partition wall disposed in said cavity dividing the cavity into a plurality of bottle-receiving compartments and elongate, thin strip like bottom members disposed in the bottom end of each of said bottle-receiving compartments with the planes thereof disposed in a vertical direction; said side walls, said partition wall and said bottom members being connected with each other through thin wall portions.

BACKGROUND OF THE INVENTION

The present invention relates to a collapsible plastic bottle-carrying container.

In selling a bottled beverage, e.g. a bottled juice, in a lot (for example, in a half dozen), it is customary to use a portable container for containing the bottles therein. For this purpose, paper containers have been developed heretofore but these conventional paper containers are not economical because they are discarded after a single usage, namely they are used only for selling a bottled beverage and not used when the empty bottles are recovered from individual households. Under the circumstances, a bottle-carrying container has been desired which is conveniently used not only for selling a bottle beverage but also for recovering the empty bottles and which is tough and durable for repeated use.

SUMMARY OF THE INVENTION

The present invention contemplates the provision of a bottle-carrying container of plastic material which is durable to be used repeatedly and collapsible for storage when not in use.

According to the present invention, the plastic-made bottle-carrying container has four vertical side walls which are connected with each other at the corners through thin wall portions defining a cavity of substantially rectangular horizontal cross-section, and in the cavity is disposed at least one partition wall by which said cavity is divided into a plurality of bottle-receiving compartments. The partition wall is connected with any one of the side walls at each vertical edge thereof through a thin wall portion. In the lower portion of each bottle-receiving compartment, defined by the side walls and partition wall, is provided at least one bottom member having a slightly elongate cross section in a vertical direction, said bottom member being also connected with the side wall or partition wall through a thin wall portion. The container of the present invention having a structure as described above can be collapsed by folding the respective members one on another at the thin wall portions.

BRIEF DESCRIPTION OF THE DRAWINGS

FIGURE 1 is a perspective view of a preferable embodiment of the container according to the present invention, with a portion broken away to show the interior of the container;

2

FIGURE 2 is a side view, partly broken away, of the container shown in FIGURE 1;

FIGURE 3 is an end view, partly broken away, of the container shown in FIGURE 1;

FIGURE 4 is a cross section taken along the line IV—IV of FIGURE 2; and

FIGURE 5 is a view, similar to FIGURE 4, of the container in an intermediate position during collapsing.

DESCRIPTION OF A PREFERRED EMBODIMENT

As shown in the drawings, the bottle-carrying container 1 of the present invention has four side walls, 2, 2', 3, 3' which are connected with each other at the corners through thin wall portions 4 defining a substantially rectangular cavity. The cavity interior of the side walls is equally divided into two sections widthwise by a longitudinal partition wall 5 which is connected with the side walls 3, 3' at the opposite edges respectively through thin wall portions 6. Each of the sections separated by the partition wall 5 is further equally divided into three sections longitudinally by two transverse partition walls 7, whereby three substantially square bottle-receiving compartments 8 are formed on each side of the longitudinal partition wall 5. Each of the partition walls 7, as shown in FIG. 4, has one end connected with the side wall 2 or 2' through a thin wall portion 9 and the other end with the partition wall 5 similarly. In the bottom end of each bottle-receiving compartment 8 are provided two thin strip-like bottom members 10 which are extending transversely with the planes thereof disposed in a vertical direction. As may be apparent from FIG. 4, the bottom members 10 each have one end connected with the side wall 2 or 2' through a thin wall portion 11 and the other end with the partition wall 5 similarly through a thin wall portion 11. The partition wall 5 extends upwardly to provide a handle 12 as shown in FIGS. 1, 2 and 3.

The container of this invention is molded integrally of a soft plastic material and used in the position shown in FIGS. 1 to 4. When not in use, the container may be collapsed simply by a force applied thereon in directions A and A' as shown in FIG. 5. The collapsing of the container can be attained very easily since the bottom members 10 each consist of an elongated thin strip and are positioned with their planes disposed in a vertical direction, and further the respective members are connected with each other through the thin wall portions.

What is claimed is:

1. A collapsible plastic bottle-carrying container comprising four vertical side walls connected with each other through thin wall portions so as to define a cavity of rectangular horizontal cross-section, at least one partition wall so disposed as to divide said cavity into a plurality of bottle-receiving compartments and having the opposed vertical edges thereof connected integrally with opposed ones of said side walls through thin wall portions, and at least one elongate thin strip-like bottom member disposed transversely of the bottom end of each of said bottle-receiving compartments with the plane thereof disposed in a vertical direction and connected with one of said walls at each end through a thin wall portion.

2. A collapsible plastic bottle-carrying container comprising four vertical side walls connected with each other through thin wall portions so as to define a cavity of rectangular horizontal cross-section, a first vertical partition wall disposed in said cavity longitudinally thereof equally dividing said cavity into two sections widthwise, at least one second vertical partition wall disposed in each of said equally divided sections transversely thereof equally dividing the respective sections into a plurality of bottle-receiving compartments of substantially square horizontal cross-section, and at least one elongate thin strip-

like bottom member disposed transversely of the bottom end of each of said bottle-receiving compartments with the planes thereof disposed in a vertical direction, said first partition wall having the opposed vertical edges thereof connected integrally with opposed ones of the side walls through thin wall portions, said second partition walls each being connected integrally at one vertical edge thereof with another of said side walls and with said first partition wall at the other vertical edge through a thin wall portion respectively, and said bottom members each being connected integrally with one of said side walls at one end and with said partition wall at the other end through a thin wall portion respectively.

3. A collapsible plastic bottle-carrying container as defined in claim 2, wherein said first partition wall extends upwardly to provide a handle. 15
